Application February 7, 1955, Serial No. 486,558

4 Claims. (Cl. 28—28)

This invention relates to textile yarn treatment and more particularly to novel slashers of the hot air dryer type and methods of slashing and is a continuation-in-part of my application S.N. 307,048, filed August 29, 1952, now Patent No. 2,752,660.

In the drying of textile yarns such as cotton or wool, for example, particularly in the so-called wet-splitting slasher, it is desirable to keep the several thousand individual yarns of the yarn sheet separated from one another as much as possible, and particularly so while the yarn is being dried to a non-tacky condition. Various complicated means have been proposed for achieving this result, but the most practical approach to the problem has been by the use of a hot air type of dryer which allows some vertical separation of the yarn sheet as well as the horizontal separation common to both hot air and cylinder dryers. Such use of vertical separation made possible by the use of a hot air dryer has greatly aided in keeping separate the individual yarns while the size coating was dried to give a superior yarn less subject to breaking and shedding in the loom.

Furthermore, I have found that automatic controls may be provided in such hot air dryers to produce a yarn of surprisingly uniform moisture content. Even if the slasher be stopped for considerable periods of time, as is frequently the case in the slashing process, my novel hot air dryer through controlled humidification prevents over drying of the yarn. Therefore, I am enabled to avoid any damage to the yarns during inevitable necessary stoppages of the slasher.

For the purpose of describing further objects and features of my novel slasher and methods, reference is made to the following drawings illustrating preferred embodiments thereof, in which

Figs. 1 and 1a when taken together provide a diagrammatic cross sectional view of the novel slasher of my invention;

Fig. 2 is a side elevational view of my novel counter-current hot air dryer as used in the slasher of Figs. 1 and 1a;

Fig. 3 is a cross sectional view of a portion of the hot air dryer of Fig. 2;

Fig. 4 is a simplified general control system diagram of the slasher of Fig. 1; and

Fig. 5 is a diagrammatic cross sectional view of the dryer of Fig. 2 taken on the line 5—5 thereof when the dryer is stopped.

Referring now to Fig. 1 the hot air drying slasher of my invention includes a creel generally designated at 2, a sizing mechanism generally designated at 3, a wet-splitting mechanism generally designated at 4, a hot air dryer generally designated at 5, and a head end generally designated at 6.

The creel 2 includes a frame 8 in which are mounted a number of section or creel beams 9, herein shown as twelve in number. Such creel is preferably of the over and under type in which the alternate beams are stag-

2

gered in height from the floor to minimize the overall length of the creel, particularly when a large number of creel beams are to be used therein. In general, any conventional creel as known to those in the art may be used.

5 By the use of such a creel, each beam of which has of the order of 500 yarn ends thereon, a mass of yarn of the order of 6000 or more ends may be assembled by taking the ends of the last beam, passing them around the second to last beam, picking up the yarns on the second to last beam and so on until the ends of all the beams have been picked up to form a composite assembled mass of yarn. The yarns thus assembled are passed to size vat 3, such size vat being of any type known to the art for providing a uniform impregnation of the assembled mass of yarns.

The impregnated yarn mass then preferably passes to the wet-splitting mechanism 4, such being arranged to take the assembled mass of yarns impregnated with size, and before completely drying it, to split it by opening it into 10 a plurality of sheets corresponding to the number of beams in creel 2. Various types of wet-splitting means may be used, including wet-splitting means within the dryer itself, although I somewhat prefer to use that shown in my application S.N. 307,048, now U.S. Patent No. 2,752,660, dated July 3, 1956, if any wet-splitting mechanism at all be used.

From the wet-splitting mechanism, the yarns pass directly to my novel hot air dryer generally indicated at 5 and hereinafter fully described. Such dryer is adapted to 15 maintain a high temperature during the first passage of the separated yarns through said dryer so that such yarns from my wet-splitting mechanism will be dried beyond the tacky stage before they are reassembled. After reassembling, drying is continued through two further passes 20 of the apparatus, carrier rolls 11 and 13 being provided in such drier so that the passes may be arranged in vertical relation with one another to keep the over all length relatively short.

From the dryer 5 the assembled yarn ends pass to the 25 head end generally indicated at 6 which may be any conventional type as known to the art. Such head end has a frame 7 on which may be mounted a loom beam 16 which may be driven by a suitable motor 22, such slasher head end being provided with delivery and press rolls 17, 18, and 19 driven by a suitable motor 24. A yarn moisture detecting device 140 is preferably provided with the slasher, such device having a detector roll 20 mounted on the head end adjacent press roll 17 so that the yarn will be nipped therebetween to enable its moisture content to be determined by suitable means known to the art.

The sheet of yarns is driven through the slasher by suitable power drive means comprising three motors, a sizing mechanism motor 26 and the two head end motors 22 and 24. As is known in this art, it is essential to arrange such motors so that they may be stopped and started without appreciably varying the tension on the sheet of yarn and that they, while running, maintain a substantially uniform tension. As hereinafter more fully explained, I have provided novel control means so that when said motors are stopped or started, the humidifying means in the hot air dryer are operated, such arrangement being effective to prevent damage to the yarns when the slasher is stopped or started as is frequently required during operation of such machines, as for example to tie broken yarns on the beams in the creel as such ends appear.

The major components of the above described slasher need not be connected mechanically to one another except through the yarns, although electrical wiring and controls interconnecting the separate units of the combination are of course essential—all as is more fully herein-after explained.

My novel hot air dryer 5, as best shown in Figs. 2, 3, and 5 is positioned immediately following the wet-splitting mechanism 4 if one be used, in order to dry the yarns so that they may be wound on a loom beam by the head end 6. The hot air dryer in general has three separate yarn passes, A, B, and C, each of which has its own individual air recirculating and heating means, such three passes each being maintained at different temperatures for most efficient drying as hereinafter more fully explained. In general, the dryer includes a frame 30 having mounted therein three pairs of plenum chambers one above the other, the entire dryer preferably being enclosed within insulating surfaces 31 having suitable openings for the passage of yarns into and out of the dryer. The lower pair of said plenum chambers includes a lower plenum chamber 40, and an upper plenum chamber 42 spaced from the lower plenum chamber, the space between said chambers being sufficient to allow the passage (pass A) of the separated sheets of yarn through opening 32 in frame 30 from the wet-splitting mechanism 4.

The second pair of plenum chambers includes a lower plenum chamber 50 immediately above and preferably in contact with plenum chamber 42, and an upper plenum chamber 52 spaced therefrom at a distance sufficient to permit the passage (pass B) of the assembled sheet of yarn between such chambers. A carrier roll 11 is provided mounted on frame 30 at the end of the dryer opposite to the wet-splitting mechanism 4, such roll being of a diameter sufficient to guide the yarns from the space between plenum chambers 40 and 42 (pass A) into the space between plenum chambers 50 and 52 (pass B).

A third pair of plenum chambers is provided above plenum chambers 50 and 52, such chambers including a lower plenum chamber 60 preferably in contact with plenum chamber 52, and an upper plenum chamber 62 spaced therefrom forming a passage (pass C) for the assembled sheet of yarns. A second carrier roll 13 is provided mounted on frame 30 to guide the sheet of yarns passing between plenum chambers 50 and 52 (pass B) into the space between plenum chambers 60 and 62 (pass C). A third carrier roll 15 is provided at the end of plenum chambers 60 and 62, such roll being adjacent an opening 33 in frame 30 to allow the passage of the dried assembled sheet of yarns out of the dryer. Preferably, an upper air chamber 38, as hereinafter more fully explained, is provided above upper plenum chamber 62 and insulated therefrom, with openings 39 at the sides of the other of said plenum chambers into it.

The plenum chambers 40 and 42, 50 and 52, and 60 and 62, as best shown in Fig. 2 are all identical in construction and include a generally rectangular enclosure having a substantially horizontal outer operating surface adjacent the area through which the yarns pass. Such operating surfaces include a plurality of louvers 34 extending transversely of the apparatus, the louvers forming openings which are narrowest at the operating surface and expand inwardly toward said enclosure. The members 36 extending between said louvers are flat on the operating surface and smoothly rounded at their interior surface. Such an opening provides a smooth non-turbulent air flow which is most effective in its drying action of the yarns passing and spaced from said surface.

In order to provide generally uniform air flow within the plenum chamber itself so that each louver is provided with air at the same pressure, the top and bottom surfaces of said chamber are constructed closer together at the end opposite the input ends of such chamber.

Each of the pairs of plenum chambers is provided with separate heater and blower systems including appropriate duct work; the lower plenum chambers 40 and 42 by heater and blower 46, having output ducts 47 and 48 to plenum chambers 40 and 42 respectively, and a return duct 49 from the end of pass A back to said heater and blower 46. Plenum chambers 50 and 52 are provided with a heater and blower 56 having output ducts

57 and 58 for providing heated air to plenum chambers 50 and 52 respectively, a return duct 59 being provided to return the air from the end of pass B back to heater and blower mechanism 56. A third heater and blower 66 is arranged to provide air to plenum chambers 60 and 62 through output ducts 67 and 68 respectively, a return duct 69 being provided from the end of pass C back to heater and blower mechanism 66. Suitable filters 81 for removing dust and lint are provided for each of the heaters and blowers to clean continuously the recirculated air.

In addition to the three separate blower systems, further means are arranged for continuously providing for exhaust of moisture laden air from pass A and for intake of fresh air into pass C as well as means for providing for movement of air between the individual passes as air is exhausted from pass A. Accordingly a duct 70 having a damper 72 is provided between pass B return duct 59, and pass A heater and blower 46, such damper being adjusted in accordance with the desired operating conditions to return a small part of the air passing through pass B return duct 59 to heater and blower 46. The damper 72 may be of the draft operated type, so that it is open only when air is being exhausted from pass A. Likewise a duct 74 is provided between pass C return duct 69, and pass B return duct 59, a damper 76 similar to damper 72 being provided in said duct to allow the movement of a portion of the air in pass C return duct 69 to be transferred to heater and blower mechanism 56. An exhaust duct 78 is provided connected to pass A return duct 49, said duct being provided with a damper 80 which is automatically operated by solenoid 82 as hereinafter more fully explained. When such exhaust damper is open to allow air to be exhausted from pass A, air is caused to flow through interconnecting ducts 70 and 74 between passes A and B, and B and C respectively, and air is drawn into pass C through opening 33 in frame.

Referring now also to Fig. 4, steam coils 44, 54, and 64, are preferably used as heaters in heaters and blowers 46, 56, and 66 respectively as simple means for regulating the temperature of the air passing through said heaters and blowers, since the temperature of the steam in such coils will be proportional to the steam pressure and such pressure may be regulated by suitable control means. A main steam line 84 provides steam for said coils. Such control means includes a temperature responsive device associated with each of the heaters and blowers 56 and 66 respectively, the temperature responsive device 100 being placed at the output of heater and blower 66, say in output duct 67 and temperature responsive device 110 being placed in output duct 58 of pass B heater and blower 56. A third temperature responsive device 120 for controlling the temperatures within pass A is placed in exhaust duct 78 since the temperatures provided at the output of pass A heater and blower mechanism 46 are usually too high for a conventional temperature responsive device in either of the output ducts 47 or 48 of such heater and blower. Such temperature responsive devices are connected to operate suitable valves to control the steam pressures which provide heat to each of said heaters and blowers 46, 56, and 66 as hereinafter more fully explained.

The blowers of said heaters and blowers are well understood by those skilled in the art and may be driven by any suitable means, herein shown as electric motors 90 driving each of said blowers. With this arrangement, it will be seen that the air flow is countercurrent to the direction of yarn travel in that air is progressively moved from pass C back to pass A, gathering an increasing amount of moisture as it dries the yarns, and finally is exhausted from pass A after it has taken up its maximum amount of moisture. The yarns as they enter pass A are in their wettest condition and hence relatively high temperatures may be used in drying them in pass A.

in order to accomplish as much drying as possible. I have found that the temperature maintained in pass A may be as high as 300-350° F. without danger of damage to the yarn. The subsequent passes are maintained at lower temperatures, for example, if pass A is maintained at 300° F., pass B may be maintained at 250° F., and pass C at 180° F.

As is known, if the yarns are overdried in a slasher they will be damaged, so that it is essential that the slasher be operated at all times so that the yarn therein will not be overdried. When the slasher is operating and the yarns are passing through the hot air dryer, the moisture present in the freshly sized yarn is continuously evaporated and so tends to reduce the temperature of the air in the dryer. Thus, the temperature of the exhausted air provides an indication of moisture content of the yarn. The various control means, particularly the exhaust duct temperature responsive device 120 controlling the exhaust damper 80, provide the optimum moisture content of the yarns as they leave the dryer at the end of pass C, by opening said damper 80 at a predetermined minimum temperature which indicates too high a yarn moisture content and closing the damper at a predetermined maximum temperature which indicates too low a yarn moisture content. When the slasher is stopped with yarns in the dryer, however, moisture will not be continuously supplied and, if the yarns are stopped for too long a period of time, there is a real danger that they will be overdried, as, even through the various heating coils be turned off and the damper 80 be closed, the dryer structure will retain a sufficient amount of heat to overdry the yarns in a relatively short time.

Accordingly, in order to avoid all danger of overdrying the yarns even when the slasher is stopped, I have found it desirable to provide a controlled source of moisture within the dryer from which moisture may be supplied to the yarns when the slasher is stopped with yarn in the hot air dryer. Such means for supplying moisture may be a humidifying coil 122 within the dryer, such coil, for example, including a perforated pipe supplied with steam from main steam line 84 through a suitable control valve 124 operated as hereinafter more fully explained. By such means, yarns may be held indefinitely in my novel dryer when the slasher is stopped, without any danger of damage to such yarns, and at the same time slasher temperatures may be maintained at their optimum.

Thus, when the slasher is running a portion of the air which is recirculated in pass C will continuously be drawn into pass B where it is heated up by heater and blower mechanism 56 to a higher temperature with a consequent increase in its drying capacity. In turn a portion of the air from pass B is continuously drawn into pass A. The final exhaust of the air from pass A is through exhaust damper 80 which damper is controlled by temperature responsive device 120 to maintain a desired moisture content in the yarn. Thus in pass C the yarn is coolest and dryest and is acted upon by the lowest temperature air. As the air in that pass tends to become overladen with moisture it is drawn into pass B where through reheating to a higher temperature it is endowed with additional drying capacity. Here the same thing happens as the saturated air is drawn into a pass A where, once again, through reheating, its drying capacity is increased. The temperature responsive devices 100, 110, and 120 together with exhaust damper 80 thus control the temperatures with each of the three passes by continuously adjusting the temperatures of the heaters within heaters and blowers 46, 56, and 66 as well as operating damper 80 to exhaust the amount of fully saturated air from pass A necessary to control the yarn moisture content and thus to draw unsaturated air into pass C.

The moisture content of the yarn may be determined just before it is wound up on beam 16 by any one of a number of well known means, for example of the

type which measures the electrical resistance of the yarn (which resistance is a function of yarn moisture content) as it passes between the head end press roll 17 and the detector roll 20 and provides an output signal responsive to the moisture content of the yarn. Thus, such a yarn moisture responsive device 140 may be connected to the detector roll 20 to provide an output signal which may appear as on indicating dial 142.

When the slasher is stopped with a sheet of yarns therein, the essential moisture is provided by humidifying coils 122, the supply of steam to such coils being controlled by the temperature responsive device 120 which acts together with exhaust damper 80 as above explained so that the yarns may be held indefinitely under the same moisture conditions as when the slasher is running, say no less than about 6.0% and preferably about 8.0% moisture in cotton yarn. Also, as shown in Fig. 5, the heated air will tend to rise into chamber 38 through openings 39 so that the yarn temperatures will be reduced, this being particularly important in case of failure of the other protection devices, such as the steam coils and blowers.

In Fig. 4 I have shown a simplified diagram of a suitable control and driving means for my novel slasher. Referring to said figure, three driving motors are provided therein for moving the yarns through the slasher, a size mechanism motor 26, beam motor 22, and a delivery roll motor 24, the purpose of the former motor being to unreel the sheets of yarn from the beams in the creel, the delivery roll motor to move the sheets of yarn from the sizing mechanism to the head end through the wet-splitting mechanism and the hot air dryer and the beam motor to wind up the sheets of yarn on the loom beam. As is well understood in the art, it is essential to control such motors to provide a constant and uniform tension from the sizing mechanism through to the head end as well as to provide means for stopping and starting such motors without substantial change in the tension to avoid damage to the yarn ends, none of such means being shown herein, the motors merely being shown as operated from a suitable source of power at terminals 130 through a single pole double throw switch 132 having one terminal 132-1 arranged to operate said motors when the slasher is running. The blower motors 90 are operated continuously while a sheet of yarn is in the slasher.

In order to stop and start my novel slasher, it is essential to operate the humidifying means on the hot air dryer. Hence the second terminal 132-2 of switch 130 is arranged to operate valve 124 for supplying steam from main steam line 84 to humidifying coils 122 within the hot air dryer. Since an appreciable time may elapse before it is necessary to provide additional moisture through the dryer through said humidifying coils, I prefer to provide a switch means 126 operated by exhaust damper 80 in series with said valve 124 so that said valve will not be operated until exhaust damper 80 is closed by its control means.

The temperature responsive devices 100, 110, and 120 are used to control steam valves to supply steam to heating coils within their associated heater and blowers. Thus, temperature responsive device 100 operates valve 101 to connect the main steam line 84 to the steam coil 54 of heater and blower 56, the temperature responsive device 110 operates valve 111 to connect the coil 64 of heater and blower 66 to the main steam line 84; and temperature responsive device 120 operates steam valve 121 to supply steam to the coil 44 of heater and blower 46. In addition temperature responsive device 120 is arranged to operate exhaust damper solenoid 82 so that the damper 80 will be moved to permit saturated air to be exhausted through duct 78 from pass A said temperature responsive device normally being connected to said solenoid through terminal 134-1 of selector switch 134. Humidifying coil 122 will then automatically operate.

when the slasher is stopped to supply moisture to the dryer as above described, such coil being provided with steam through a valve 124.

The moisture output device 140 is itself well known in the art and will not herein be further described. It may also be used to control the temperature of the heating coils or the speed of the slasher drive motors in response to yarn moisture content, if such be desired, its use for such latter purposes being well known.

By the above described control means, the slasher will maintain its optimum drying while running, and yet it may be readily stopped and started, by actuating—in this simplified showing—a single switch 132, without damage to the yarns in my novel hot air dryer since the various above described means are automatically actuated by said switch.

It will be apparent to those skilled in the art that various other modifications may be made within the spirit of my invention and the scope of the appended claims.

I claim:

1. In a slasher having sizing means for impregnating a mass of yarns with a sizing composition, air drying means including a plurality of heated chambers in vertically stacked relation for drying said sized mass, power driving means for moving said mass through said sizing means and said drying means, means for heating said chambers independently of one another to provide progressively decreasing temperatures of said chambers from the lowest to the highest chamber of said drying means, means for feeding the mass of yarn to be dried to the lowest of said chambers and progressively upwardly through said chambers to the highest thereof, means for passing heated air between said chambers from the highest to the lowest thereof, exhaust air passage means for passing heated air from the lowest of said chambers, damper means mounted in said exhaust air passage for controlling the exhaust of air from said passage, humidifying means in said lowest chamber operable to supply moisture to said mass, damper control means including temperature responsive means mounted in said exhaust passage responsive to the temperature of air passing through said exhaust passage for operating said damper to decrease the exhaust of air through said exhaust passage upon increase in temperature of air passing through said exhaust passage and humidifying control means including switch means actuated by stopping of said power driving means and by said temperature responsive means to actuate said humidifying means to supply moisture to said yarn mass to prevent overdrying of said yarns upon said mass being stopped in its advance through said air drying means and having more than a predetermined temperature of exhaust air.

2. In a slasher having sizing means for impregnating a mass of yarns with a sizing composition, air drying means including a chamber for drying said sized mass of yarns, said chamber having humidifying means operable to supply moisture to a mass of yarns therein and control means therefor, and power driving means for moving a mass of yarns through said sizing means, said control means including means actuated by stopping of said power driving means and sensing means responsive to the temperature of air in said chamber to actuate said humidifying means to supply moisture to said yarn mass

to prevent overdrying of said yarns when a mass is stopped in said chamber and the air in said chamber is above a predetermined temperature.

3. In a slasher having sizing means for impregnating a mass of yarns with a sizing composition, air drying means including a chamber for drying said sized mass of yarns, said chamber having an exhaust air passage, damper means mounted in said passage for controlling the exhaust of air from said passage, damper control means, and power driving means for moving a mass of yarns through said sizing means, said damper control means including means responsive to the temperature of air passing through said exhaust passage for operating said damper to decrease the exhaust of air through said passage upon increase in said temperature.
4. In a slasher having sizing means for impregnating a mass of yarns with a sizing composition, air drying means including a chamber for drying said sized mass of yarns, said chamber having an exhaust air passage, damper means mounted in said passage for controlling the exhaust of air from said passage, damper control means, humidifying means operable to supply moisture to a mass of yarns in said chamber and humidifying control means therefor, and power driving means for moving a mass of yarns through said sizing means, said damper control means including means responsive to the temperature of air passing through said exhaust passage for operating said damper to decrease the exhaust of air through said passage upon increase in said temperature.
5. In a slasher having sizing means for impregnating a mass of yarns with a sizing composition, air drying means including a chamber for drying said sized mass of yarns, said chamber having an exhaust air passage, damper means mounted in said passage for controlling the exhaust of air from said passage, damper control means, humidifying control means being actuated by stopping of said power driving means and sensing means responsive to the temperature of air in said chamber to actuate said humidifying means to supply moisture to said yarn mass to prevent overdrying of said yarns when a mass is stopped in said chamber and the air passing through said chamber exhaust passage is above a predetermined temperature.
